(57) **CLAIM**

The ornamental design for a miter saw, as shown and described.

DESCRIPTION

FIG. 1 is a perspective view of a first embodiment of a miter saw.

FIG. 2 is a front elevational view of the first embodiment.

FIG. 3 is a rear elevational view of the first embodiment.

FIG. 4 is a left side elevational view of the first embodiment.

FIG. 5 is a right side elevational view of the first embodiment.

FIG. 6 is a top plan view of the first embodiment; and, FIG. 7 is a perspective view of a second embodiment of a miter saw.

In the above drawings, any wording or numerals shown therein does not form a part of the invention.
